Primary Examiner — Anhdao Doan(74) *Attorney, Agent, or Firm* — Meyertons, Hood, Kivlin,
Kowert & Goetzel, P.C.; Eric B. Meyertons(57) **CLAIM**The ornamental design for an x-ray marker, as shown and
described.

DESCRIPTION

FIG. 1 is a front perspective view of an x-ray marker embodying the new design;

FIG. 2 is a front view of the device shown in FIG. 1.

FIG. 3 is a back view of the device shown in FIG. 1.

FIG. 4 is a right side view of the device shown in FIG. 1.

FIG. 5 is a top side view of the device shown in FIG. 1; and,
FIG. 6 is a bottom side view of the device shown in FIG. 1.
The letters presented in broken lines in FIG. 1 and FIG. 2 are
only to illustrate the placement of the radiopaque indicia on
the devices.Only a right side view is shown of the device because the left
and right side views are identical.

1 Claim, 1 Drawing Sheet
